GARMENT AND METHOD OF MAKING
THE SAME

Albert George Neel, Nazareth, Pa., assignor to
Nazareth Mills, Incorporated, Nazareth, Pa., a
corporation of Pennsylvania

Application March 13, 1946, Serial No. 654,021

7 Claims. (Cl. 2—121)

1

My invention is an improved body garment, and method of making the same, to provide shoulders formed of overlapping layers of fabric stretchable in transverse directions to permit the expansion of the neck opening for the passage of the head of the wearer.

In the preferred embodiment of my invention I utilize a body blank such as is used for making garments of conventional type and overlap front shoulder straps thereof with flaps integral with and projecting laterally from sleeve members and connected with and providing anchorages for back shoulder straps of the body blank. Similarly, the back shoulder straps of the body blank are overlapped by flaps integral with and projecting laterally from the sleeve blanks and connected with and providing anchorages for the front shoulder straps.

The shoulder straps and sleeve flaps are preferably formed of knitted fabric and the wales of the sleeve flaps extend transversely to the wales of the shoulder straps, so that the shoulder straps stretch primarily laterally of the garment and the sleeve flaps stretch primarily longitudinally of the garment. This transverse stretchability of the overlapped straps and flaps facilitates the expansion of the neck opening substantially to the full width of the garment between the armholes, and the resiliency of the fabrics tends to restore the straps and flaps to normal overlapping position and proper relation of the shoulder inner edges to the base of the neck of the wearer.

The principles and characteristics of my invention and the manner and process of making, constructing and using my improved garment will further appear from the accompanying drawings and the following explanation of the best mode in which I have contemplated applying such principles.

In the drawings, Fig. 1 is a front view of a child's waist or undershirt embodying my invention; Fig. 2 is a back view of the garment shown in Fig. 1 with parts broken away; Fig. 3 is a pattern for guiding the cutting of a flattened tubular fabric to form a blank from which a conventional garment may be made but which by my invention is adaptable to the manufacture of garments having overlapping shoulder straps and flaps providing an expansible neck; Fig. 4 is a plan view of a blank cut according to the pattern of Fig. 3 after the original edge folds of the blank have been shifted 90° circumferentially of the blank and the blank refattened, and from which a conventional garment might

2

be made by seaming together the tops of the corresponding shoulder straps; Fig. 5 is a pattern for guiding the cutting from folded fabric of a sleeve blank having integral flaps in accordance with my invention; Fig. 6 is a plan view of an unfolded sleeve blank and integral flaps cut from folded fabric according to the pattern of Fig. 5; Fig. 7 is a fragmentary back view of the upper portion of the blank shown in Fig. 4 with the top edges of the rear shoulder straps attached to the end edges of flaps extending laterally from armhole edges of front sections of sleeves; Fig. 8 is a fragmentary top plan view of the partly assembled garment shown in Fig. 7 after the top edges of the front shoulder straps have been attached to the end edges of folded over sections of flaps extending laterally from the armhole edges of rear sections of sleeve blanks; Fig. 9 is a fragmentary view of the partly assembled garment shown in Fig. 8 after the sleeves and attached flaps have been folded into positions for seaming the sleeves to the body; and Fig. 10 is a longitudinal sectional view taken on the line 10—10 of Fig. 9.

25 My invention is applicable to garments of various types but is particularly applicable to underwear having a body composed of fabric having a lateral stretch, viz., a stretch circumferentially around the garment, and in the preferred embodiment of my invention shoulder straps composed of fabric stretchable laterally of the garment are secured to and anchored by flaps composed of fabric having its principal stretch longitudinally of the garment. Such transverse stretchings of the shoulder straps and anchoring flaps may be conveniently provided by cutting the body and shoulder straps from weft knit fabric having its wales extending longitudinally of the shoulder straps and body and cutting the sleeves and flaps from weft knit fabric so that the wales thereof extend transversely of the flaps, viz., lengthwise of the sleeves.

45 The body of the garment is preferably cut from tubular fabric which when flattened has a width approximating the width of the finished garment, and which may be conveniently cut by laying a conventional pattern, such as shown in Fig. 3, lengthwise along the top of a stacked series of flattened tubular fabrics.

50 The pattern, and the blanks cut in accordance therewith, have substantially parallel side edges 1 and 2, a bottom edge 3 which may be of any desired contour, and a top edge 4 which is substantially normal to the side edges 1 and 2. The 55 upper corners of the pattern and fabric blank

3

are cut on arcuate lines 5 and 6, which may be of equal or unequal length or contour, to provide front and back neck recesses of desired depth. A segment is excised from each layer of the blank along the curved downwardly converging lines 7 and 8 to form armholes in the usual manner.

A blank so cut is turned about an axis so that the sections forming the original edges 1 and 2 are brought to the center of the front and back of the reflatten blank, whereby the neck recesses 5a and 6a formed by the cuts along the lines 5 and 6 are brought into complementary relation to form a neck opening and each pair of edges 1a and 8a formed by the cuts along the lines 7 and 8 are brought into complementary relation to provide armholes on opposite sides of the garment. The fabric lying between the plane of the neck recess 5a and armhole edges 7a provide front shoulder straps 9 having top edges 10, and the fabric sections lying between the plane of the neck recess 6a and the armhole edges 8a form back shoulder straps 11 having top edges 12.

The top edges 10 and 12 might be seamed to one another to make a conventional undergarment, but in accordance with my invention such edges 10 and 12 are not secured directly to one another, but are respectively secured to the respective juxtaposed end edges 13 and 14 of flaps 15 and 16 formed integrally on the front and back sections of a sleeve member 17. The flaps 15 and 16 project laterally from the armhole edge 18 of the sleeve member 17 and the members 15, 16 and 17 may be conveniently shaped by laying a pattern, such as shown in Fig. 5, upon a folded strip of knitted fabric having wales extending substantially parallel to the fold line of the fabric, viz., in the direction of the length of the sleeve and of the width of the flaps 15 and 16. The pattern is, of course, turned in cutting the sleeves of a pair.

The flaps 15 and 16 have preferably somewhat the contour of isosceles triangles and may be partially severed from the sleeve member 17 by notches 19 and 20 to facilitate the manipulation of the parts.

The top edges of the shoulder straps are connected with the wider ends of the sleeve flaps in any desired sequence but so that the front shoulder strap edges 10 are connected to the edges 14 of the sleeve back flaps 16 and the back shoulder strap edges 12 are connected to the edges 13 of the sleeve front flaps 15.

As indicated by way of example in Fig. 7, the edges 12 and 13 may be first seamed to one another in abutted or overlapped relation by seams extending transversely of the garment and with the wales of the sleeve flaps 15 extending transversely to the wales of the back straps 11.

The flaps 16 may then be inserted between the front 1a and the back 2a of the garment and the flap section adjacent to the edge 14 bent over to bring the edges 10 and 14 into juxtaposed, abutted or overlapped relation and with the wales of the flaps 16 extending transversely to the wales of the front straps 10, as illustrated in Fig. 8. The edges 10 and 14 are then seamed, or otherwise secured to one another; the seams being parallel with but slightly spaced from the seams joining the edges 12 and 13.

The sleeve blank 17 may now be folded over to bring the armhole edge 18 of the sleeve blank 17 into seaming relation to the armhole edges of the front and back body fabric, as indicated

4

in Fig. 9. The complementary edges of the body, sleeves and flaps, and the complementary edges of the sleeves, are then seamed to one another to produce the garment shown in Figs. 1 and 2.

Any desired reinforcing stitches and fasteners may be applied to the garment as indicated in Figs. 1 and 2.

The portions of the sleeve flaps adjacent to the armholes are anchored in the armhole seams and provide elastic and resilient anchorages for the shoulder straps with which the respective flaps are connected. The edges of the flaps remote from the armholes are free and provide continuations of the edges of the neck recesses 5a and 6a.

By my improved construction, and particularly by providing strap anchoring flaps capable of stretching longitudinally of the garment, the head opening may be expanded to substantially the full width of the garment between the tops of the armholes. By pulling on the front 1a and back 2a after the neck opening has been expanded, the flaps and straps are restored to overlapping relation and the sides of the neck opening again restored to normal.

My invention minimizes the amount of fabric required for making an expandible neck garment, and permits the use of standard body blanks in the construction thereof.

Having described my invention, I claim:

1. A body garment having front and back shoulder straps, each of said straps having a top edge adjacent to the medial horizontal shoulder line, and a sleeve member having a pair of flaps integrally connected with armhole edges of said member, said flaps having adjacent end edges when said sleeve member is folded to form the front and back of a sleeve, the top edge of a back shoulder strap being connected with an end edge of the sleeve front flap and the top edge of a front shoulder strap being connected with an end edge of the sleeve back flap.

2. A body garment having a front and a back each having a pair of shoulder straps with top edges and wales extending transversely to said edges, and a pair of sleeve members each having a front and back with integral flaps projecting laterally from the armhole edges thereof said members and their integral flaps having continuous wales, the top edges of the front shoulder straps being connected with the ends of the sleeve back flaps and the top edges of the back shoulder straps being connected with the ends of the sleeve front flaps and the wales of the straps extending transversely to the wales of the flaps connected therewith.

3. A body garment having a front section and a back section, at least one of said sections having a pair of shoulder straps with top edges extending substantially transversely of the garment, a pair of sleeves each having front and back sections and at least one section of each sleeve having an integral flap projecting laterally from the armhole edge thereof and having an end edge extending transversely to the armhole edge, the top edge of each of said shoulder straps being connected with an end edge of a sleeve flap aforesaid.

4. A garment comprising a body having a front and a back and containing an armhole, said garment having a section adjacent to said armhole and provided with a shoulder edge transverse to the length of said body, said section having a stretch primarily in one direction, and a sleeve having its upper edge adjacent to said shoulder

edge, said sleeve being attached to said body along the edge of said armhole and having an integral flap projecting laterally from said armhole and connected with the transverse edge of and anchoring said section, said flap having a stretch primarily transverse to the direction of stretch of said section.

5. A sleeve blank for a garment comprising a sleeve-forming member having an armhole edge and integral flaps projecting laterally from said armhole edge said flaps having wales continuous with the wales of the sleeve forming member, said flaps having approximately the form of isosceles triangles with their bases adjacent to one another.

6. In a method of forming a garment from a body blank having a front and a back each having shoulder sections with juxtaposed edges and a sleeve blank having a front and back having an armhole edge and provided with lateral flaps having edges extending transversely to the armhole edge, the steps which comprise attaching a transverse edge of a front lateral flap to an aforesaid edge of a back shoulder section and attaching a transverse edge of a back lateral flap to an aforesaid edge of a front shoulder section.

7. In a method of forming a garment from a body blank comprising front and back members having top edges and a sleeve blank having an armhole edge with members projecting therefrom and having approximately the form of isosceles triangles with their bases adjacent to one another, the steps which comprise seaming one of said bases to one of said edges with the abutted members flat and seaming the other of said bases to the other of said edges while one of such members is bent over on itself.

ALBERT GEORGE NEEL.
